UNITED STATES PATENT OFFICE.

MICHAL PALIJ, OF CHICAGO, ILLINOIS.

MASK.

1,401,724.

Specification of Letters Patent. Patented Dec. 27, 1921.

Application filed February 24, 1921. Serial No. 447,528.

To all whom it may concern:

Be it known that I, MICHAL PALIJ, a citizen of Ukraine, residing at Chicago, in the county of Cook and State of Illinois, have invented certain new and useful Improvements in Masks, of which the following is a specification.

This invention relates to certain new and useful improvements in masks and has particular reference to a mask for inclosing the face of a person with the edges of the mask intimately contacting the head to seal the face to the atmosphere, and being provided with air or oxygen supply means under control of the wearer of the mask.

A further object of the invention resides in the provision of a mask embodying a frame adapted to be tightly secured to the head of the wearer with a hinged front plate carried by the frame and including a wall of transparent mica or pyroxylin material, the mask being provided with a manually operable valve to regulate the supply of oxygen or air to the mask while ear caps are carried by the sides of the mask and are provided with hinged covers to permit the application of an absorbent material within the cap from the outer side of the mask.

This invention is especially adapted for use in factories where gases and fumes that are poisonous to a person permeate the atmosphere, the mask being as well adapted for use in mining and for any other purpose desired where it is necessary to protect the face and lungs of a person from poisonous gases.

With the above general objects in view and others that will become apparent as the nature of the invention is better understood, the same consists in the novel form, combination and arrangement of parts herein-after more fully described in connection with the accompanying drawings and in which like reference characters indicate corresponding parts throughout the several views.

In the drawings,

Figure 1 is a front elevational view of a mask constructed in accordance with the present invention with the same in operative position upon a person as indicated by dotted lines,

Fig. 2 is an enlarged front elevational view of the mask,

Fig. 3 is a top plan view thereof showing the face engaging frame of the mask,

Fig. 4 is a side elevational view of the mask with the hinged front frame moved to its open position as indicated by dotted lines,

Fig. 5 is a cross sectional view taken on line V—V of Fig. 3 showing the needle valve for controlling the supply of oxygen or air to the mask and the padded ear caps at opposite sides of the mask,

Fig. 6 is a detail sectional view taken on line VI—VI of Fig. 4 showing the catch lever for holding the hinged frame in fixed position on the mask frame, and

Fig. 7 is a detail sectional view taken on line VII—VII of Fig. 6.

Briefly described, a mask constructed in accordance with this invention embodies a frame carrying straps adapted for engagement with the head of a wearer for holding the frame in correct position, the frame embodying a temple engaging section and cheek and chin engaging sections adapted to intimately contact the face of the wearer to prevent the passage of air between the mask frame and the head.

A front frame is hinged to the frame fixed to the head of the roller and includes a wall of mica or pyroxylin material fully transparent so as not to interfere with the vision of the wearer while an ear cap is carried by each side of the wall and has a reticulated hinge cover that overlies an absorbent material filling in each cap to permit the passage of sound waves and to exclude gases and the like. A source of oxygen or fresh air supply has a hose connection with a needle valve casing carried by the lower end of the hinged section of the mask so that the proper amount of fresh air may be admitted to the mask for comfort of the wearer.

Referring more in detail to the accompanying drawings, there is illustrated a gas mask embodying a frame adapted for rigid mounting upon the head of the wearer, the frame embodying a temple section 1 of arched formation as illustrated in Fig. 3, the same being preferably formed of metal and having a padding lining 2 of fabric for engaging the head, the rear ends of the section 1 being connected to the perpendicular cheek and chin engaging section 3 having a fabric lining 4. The frame is supported on the

head by a series of straps 5 adjustable in length and provided with snap fasteners to enable the mask to be securely placed in position with the sections 1 and 3 of the frame 5 snugly engaging the head of the wearer.

A hinged forward frame is carried by the rigidly mounted frame and embodies an upper arcuate section 6 carrying a central clip 7 having lugs 8 hinged to lugs 9 on the strip 10 1 as clearly shown in Figs. 1 to 4, the rear edges of the frame 6 being formed integral with the perpendicular frame 10 that overlies the frame 3 when in closed position as shown in Fig. 4. To retain the hinged frame 15 in the closed position shown, a lever 11 is pivotally mounted in lugs 12 carried by the frame section 10 and has the forward bent end 13 thereof projected through registering openings 14 in the overlapped frame sections 20 3 and 10 as clearly shown in Figs. 6 and 7, the lever 11 being tensioned by the spring 15 to hold the bent end 14 thereof projected through said openings.

A face shield or plate 16 formed of mica, 25 pyroxylin or other like transparent material is carried by the hinged frame, the front side of the shield 16 being provided with a reinforcing frame 17 of the form best illustrated in Figs. 1 and 2 inclosing the eye section 30 of the shield with the lower side of the frame curved upwardly as at 18 with the shield within the curved portion 18 bulged outwardly as at 19 to provide a clearance space for the nose.

35 An ear cap is carried by each side of the shield section 16 and as shown in detail in Fig. 5, an opening is formed in the side of the shield and covered by a reticulated plate 20 secured to the edges of said opening while 40 a tubular extension wall 21 extends outwardly of the side of the shield 16 and is closed by a hinged reticulated cover 22 confining an absorbent packing 23 within the tubular extension 21 between said cover and 45 the reticulated plate 20. The packing material 23 within the ear caps will permit a limited passage of sound waves and at the same time will prevent the passage of air through the ear cap to the interior of the 50 mask, thereby insuring against the ingress of poisonous gases to the mask.

In order to provide for a supply of oxygen or fresh air to the interior of the mask, the lower end of the chin portion thereof is provided with bracing frames 24 shown more clearly in Figs. 3 and 5, said frames carrying a perforated plate 25 set in a cut-out portion in the lower end of the mask and carrying a valve block 26 secured as at 27 to 55 the mask with an inlet nozzle 28 having a flexible tube 29 attached thereto as shown in Fig. 1, a screw needle valve 30 being threaded in the block 26 for controlling the admission of oxygen or fresh air to the mask. A 60 body strap 31 is attached to the body of the

wearer as shown in Fig. 1 and carries guide members 32 for supporting the tube 29 in proper position, the tube being of sufficient length to extend to a suitable source of oxygen or air supply from a distantly positioned 70 tank, or to a receptacle or tank carried upon the back of the wearer.

In the operation of the device, the mask incloses the face of the head with the straps 5 securely retaining the same in position. 75 Sound waves travel through the ear caps 21 and the supply of air or oxygen is admitted to the mask under control of the valve 30 through the perforated bottom plate 25 to the interior of the mask. Should it be desired to obtain access to the interior of the mask without completely removing the same from the head, the tensioned lever 11 is shifted to displace the bent end 13 from the registering openings in the frame sections 3 and 10 whereupon the forward frame section is permitted to move on its hinge mounting 8, 9 to the dotted line position shown in Fig. 4, thus giving free access to 80 the face of the wearer.

While there is herein shown and described the preferred embodiment of the invention, it is nevertheless to be understood that minor changes may be made therein without departing from the spirit and scope of the 95 invention as claimed.

What is claimed as new is:

1. A mask of the type described comprising a rigidly positioned frame, head straps carried thereby, a forward frame hinged to 100 said rigid frame and carrying a transparent shield, means for admitting air to said shield, co-operating means carried by said frames for holding the same in closed position, ear caps carried by said shield, said ear caps 105 including tubular extensions carried by the shield, a reticulated plate at the inner end of each extension, a hinged cover for the extension and a packing material between the reticulated plate and hinged cover. 110

2. A mask of the type described comprising a rigidly positioned frame, head straps carried thereby, a forward frame hinged to 115 said rigid frame and carrying a transparent shield, means for admitting air to said shield, said means including a valve block secured to the chin portion thereof, a screw needle valve within said block and a flexible hose connected to said block.

3. A mask of the type described comprising a rigidly positioned frame, head straps carried thereby, a forward frame hinged to 120 said rigid frame and carrying a transparent shield, means for admitting air to said shield, said means including a valve block secured to the chin portion thereof, a screw needle valve within said block, a flexible hose connected to said block, and a body strap for supporting the hose.

4. In a mask of the type described, a 130

rigidly positioned frame, a movable frame hinged to the rigid frame, and coöperating means carried by said frames for holding the same in closed position, ear caps carried by the movable frame and including spaced reticulated plates and a packing between said plates.

In testimony whereof I affix my signature in presence of two witnesses.

MICHAL PALIJ.

Witnesses:

WASYL TWANISZYN,
PETER P. MINDAK.
